UNITED STATES PATENT OFFICE

2,609,975

SPRING CLOSURE FOR COLLAPSIBLE TUBES

Frank A. Senger, Somerville, N. J., assignor to
Ortho Pharmaceutical Corporation, a corpora-
tion of New Jersey

Application July 16, 1949, Serial No. 105,133

1 Claim. (Cl. 222—496)

1

This invention relates to the class of collapsible tubes or containers having removable caps and particularly relates to a spring actuated closure for such tubes.

The principal object of this invention is to provide an improved spring device for closing collapsible tubes of the type generally used for containing and dispensing tooth paste, shaving cream, and other pharmaceutical preparations.

Another object of this invention is to provide a spring-action device for closing the orifice of a collapsible tube having a spring positioned inside the said tube, which device yields to pressure on the tube and permits the tube contents to be expelled and upon release of pressure closes the orifice and seals the tube contents in the tube.

Other and further objects will be apparent from the following specification when taken in connection with the drawing in which:

Figure 1 is a view in elevation of a collapsible tube with the spring closure assembly in position and showing the relation of the spring closure and the cap to the body of the tube;

Figure 2 is an enlarged fragment of Figure 1, showing the position of the spring closure with the cap removed from the tube;

Figure 3 is a horizontal plan of Figure 2 showing the spring closure in position;

Figure 4 is an inverted plan section taken on the line 4—4 of Figure 2; and

Figure 5 is an enlarged representation of the unassembled parts of the spring closure.

Still another object of this invention is to provide a spring-action device for closing the orifice of a collapsible tube which is not susceptible of easy detachment from the tube and thus is not readily lost or displaced.

Referring to the drawing and to Figure 1, which illustrates the preferred embodiment of the present invention, the reference character 2 designates a container which is ordinarily in the form of a metallic collapsible tube. The container as illustrated is provided with the usual screw-threaded neck 12 and a screw-threaded cap 4, fitted in position in threaded relation with the tube neck. The device of this invention may, however, be used on a tube in which a tube cap is not used and effectively seal the contents of the tube therein. Figure 1 also shows the relative position of the spring closure device, which in the preferred embodiment, consists of a spherical stopper 10, larger in diameter than the neck of the tube, but having a diameter of such a size that it will not pass through the neck of the tube,

2

and a spring 14 attached to the stopper 10 and positioned inside the tube.

Figures 1, 2, 3, and 4 clearly show the relationship and positioning of the spring closure device with respect to the collapsible tube. It will be seen that in the embodiment illustrated in these figures, spring member 14 is passed through a hole in the stopper and is bent at one end to prevent separation of the stopper from spring wire 14. 10 Spring wire 14 extends into the tube and then is bent at an angle greater than 90 degrees in a first bend 19, and is bent at an angle of less than 180 degrees in a second bend to make an elbow 18. Elbow 18 fits snugly against the conical part 6 15 at a position below neck 12 and above tube body 16. The spring wire then extends across the width of the tube body and is of sufficient length so that the end 20 of the spring wire fits against the side of the tube body 16 just below the point 20 where the conical part 6 of the tube body begins.

In the preferred embodiment of the spring closure device, as illustrated in the drawings, the spring may not be removed from the collapsible tube without the use of a substantial amount of 25 force, but when pressure is applied to the collapsible tube with the purpose of expelling the contents from the orifice of the tube neck, the said contents of the tube are forced against the stopper and cause the stopper to be raised above the opening in the neck with a consequent expulsion 30 of the contents of the tube. When pressure is released from the collapsible tube, the action of the spring brings the stopper back in close contact with the rim of the tube neck and effectively seals the contents within the tube and prevents evaporation of any volatile materials in the contents 35 of the tube and in general makes an air-tight seal of the tube.

The spring closure device may be readily inserted into a collapsible tube by inserting that 40 part of the spring which is adjacent to end 20 into the tube and then exerting pressure on the spring at the bend 18 in order to bring that part of the spring in approximate alignment with the other parts of the spring. In this way the whole 45 of the spring member approximates alignment and may be inserted into the neck of the tube to a sufficient distance that bend 18 slips past the narrow opening of the neck and assumes the position on the surface of the conical part of the tube, as illustrated in Figures 1 and 2. In order for 50 bend 18 to slip past the narrow opening of the neck it is necessary that portion 17 of the spring, between bends 18 and 19 be of such a length 55 that it is less than the distance from bend 19 to

the corner formed by the conical part of the tube 6 and the tube neck 12 when the spring is fully inserted into the tube and ready for use.

Stopper 10 may be fabricated of glass, rubber, or any plastic or other material which is inert with respect to the contents of the tube and may be spherical, or may have any shape which will permit of efficient closure of the tube orifice. The spring may be composed of any metallic substance, such as spring steel, having suitable spring-like character. The spring may be attached to the stopper in any suitable fashion and may be integral with the stopper.

From the description above, it will be readily apparent that a device according to the present invention may be simply constructed and economically manufactured and sold. The device may be made in different sizes to conform to the size of the tube with which it is to be used. More or less variation of the exact details of the construction is possible without departing from the spirit of this invention. It is desired, therefore, not to limit the invention to the exact form of the construction shown and described, but it is intended in the following claim to point out all the invention disclosed therein.

What is claimed is:

A spring actuated closure device for a collapsible tube, comprising in combination with a collapsible tube having a neck with an opening

5 therethrough, a cylindrical tube body closed at one end, and a conical tube part between the neck and tube body; a stopper for closing the opening in the tube neck and seated therein, a spring attached to said stopper and extending through the tube neck and into the tube with a first bend and a second bend, the spring at the point of the second bend resting against the conical tube part, and at its end resting against the cylindrical tube body at the juncture of the said cylindrical tube body and the said conical tube part; the distance between the first and second bends in the spring being less than the distance between the first bend and the juncture of the conical part of the tube with the tube neck when the spring is positioned inside the tube; the spring in position being adapted to yieldably hold the stopper against the tube neck and over the opening in the said tube neck.
